Harold Boyd Coulter, Mamaroneck, N. Y., assignor to The Dorr Company, Inc., New York, N. Y., a corporation of Delaware

Application May 1, 1935, Serial No. 19,218
Renewed November 10, 1937

11 Claims. (Cl. 209—465)

This invention relates to apparatus for the separation of settleable solids from liquids and more particularly to apparatus of the type known as bowl classifiers. Bowl classifiers are of a type of apparatus which has been on the market for several years and they have been produced in considerable numbers by the assignee of the present invention, namely, by The Dorr Company, Inc. The general type of classifier forming the basis of the invention is shown and described in the U. S. Letters Patent 1,292,237 granted January 21, 1919 covering an invention of Alfred L. Biomfield. The general type of apparatus is also illustrated in the Slade Patent 1,916,392 granted July 4, 1933.

While bowl classifiers were originally designed for and have decidedly advantageous use in the ore dressing fields, nevertheless, the use thereof has not been confined to these fields, but has extended into many other fields wherein it is desired to separate different kinds or types of solids of hydraulic mixtures containing the different types of solids, as for example, containing solids having different specific gravities or different settling rates, containing solids having different sizes, or containing solids having other peculiarly different physical or other basically different characteristics.

Bowl classifiers of the type described essentially comprise a bowl shaped section and an inclined trough section. One of these sections, as for example, the bowl section, provides what is referred to as a primary chamber and the other of these sections, as for example, the trough section, provides what may be referred to as a secondary chamber or compartment. These two chambers are in direct communication with each other through a relatively constricted opening; the general level of liquid is substantially the same in each, there existing a slight level differential primarily incident to different specific gravities of the baths in the two chambers. According to some proposed modes of operation, it is desirable that the liquid mixture undergoing treatment be introduced into the bowl section so as to have a predominating overflow over a peripheral weir with a downward passage from the bowl section into the inclined trough section of heavier or larger suspended solids. The supernatant liquid with fine solids in suspension overflows through a launder leading from the bowl section while emerged larger solids or sands are raked to discharge from the trough section.

In bowl classifiers of the type under discussion, the bowl section thereof is provided by a circular

bowl shaped tank having a marginal or boundary wall extending upwardly from the bottom or bottom portion which as usually made is in the form of an inverted cone with a centrally located discharge opening providing a restricted, but constant open communication or passageway at the lowermost portion of the bowl section, namely, between the bowl section and the trough section. The effluent launder with which the bowl section is provided is generally arranged so as to receive supernatant liquid from near the upper marginal portion of the bowl. The bowl section also has a movable settled-solids raking and conveying mechanism—sometimes referred to as mechanical rakes—turnable as a rotatable assemblage about a vertically extending axis and operable over the bottom of the tank. This turnable or rotatable assemblage is provided for raking and scraping settled solids or sediment from the diverse sections of the tank bottom and for effecting an impelling or plowing and ultimate transferring of the raked solids to the centrally disposed discharge opening. The rotatable assemblage is therefore frequently referred to as a rotary raking mechanism.

The trough section has a sloping bottom from which there upwardly extends an end wall and marginal side walls which merge into the bowl shaped tank thus combining with the bowl in completing a liquid holding structure or basin. The trough section also has operatively positioned therein an agitating and conveying mechanism—also sometimes referred to as mechanical rakes—preferably provided by a reciprocating raking and scraping mechanical element mounted and actuated so as to move in a modified or approximately D shape cyclic path in which the straight portion of the D is lowermost and parallels the sloping bottom or inclined deck of the tank and in which the bight portion of the D is uppermost with the result that the forward upward movement of the raking element takes place when the raking element is in its lowermost position, thereby effecting a forward and upward transfer of solids along the sloping bottom or inclined deck of the trough and so that during the return movement along the bight or curved portion of the D there is realized much of the agitative effect to which solids in the trough are subjected, particularly as the rakes or blades of the raking element dig downwardly into the heavier or settled solids preparatory to the succeeding forward feeding movement thereof.

The machines of the general type in question have proved exceedingly satisfactory in the fields

of endeavor to which they have been applied, but with the passing of time and with industrial progress, particularly in respect to the seeking of higher capacities and larger sizes of apparatus, there has come an opportunity for exceedingly sturdy and compact machines of unusually high capacity.

Frequently where such machines are to be employed there is limitation as to space, more specifically as to headroom, particularly in plants already in existence. Because of the facts mentioned, it has become important and advisable to design and develop an improved form of apparatus which would meet the particular and exacting requirements. The design of the present invention illustrates a construction which is relatively compact particularly as to the requirements of the headroom and it is also relatively rigid and strong. While the present design is particularly adapted for use in apparatus of relatively large capacities, it is nevertheless adaptable for employment in the smaller form of apparatus and as a substitute for the embodiments of construction as illustrated in the older patents heretofore referred to. Due to the improvement in capacity of grinding mills and the trend toward higher circulating loads, classifiers must have correspondingly higher capacities. This leads to larger sizes and changes in design and structural features of a character to commercially meet the increasingly heavier load requirements.

The desired ends above referred to are realized by a construction embodying the following features, to wit, a construction in which:

1—The structure above the bowl or tank spanning the bowl, and supported by the bowl so as to be carried thereby, is essentially relatively shallow and comprises (a) what may be referred to as two horizontally and transversely spaced horizontally and longitudinally extending main beams or girders located at opposite sides of and equally distanced from the vertically extending axis of the bowl shaped tank, or what is substantially the same thing, at opposite sides of the vertically extending axis about which the rotatable raking mechanism turns and (b) two horizontally extending cross braces or transverse members connected to and rigidly connecting the main longitudinals and located at opposite sides and equally distanced from the vertically extending axis of the bowl shaped tank. The main beams and the cross-connecting members just referred to are preferably, but not necessarily, located equal distances from the vertically extending tank axis, so that there results a box-like structural section providing a relatively square opening extending downwardly therethrough. This box-like section has been provided for two purposes, namely, in order to provide adequate support for a relatively large stationary annular supporting member of a turntable construction, to wit, a proper and adequate support for what may be referred to as a large annular turntable base upon which there is turnably mounted and carried the upper or turnable member of the turntable construction. The upper turnable member of the turntable construction is preferably provided by a hollow annular member to which there is connected and from which there depends a hollow cage-like or drum structure that extends downwardly into and through the opening provided by the box-like section.

2—The turntable construction and more par-

ticularly the annular bearing sections or raceways thereof are sufficiently large to provide a horizontal thrust bearing which can be relied upon to prevent any tilting of the parts carried by and from the turnable member thereof away from or out of the normal vertical operable alignment therefor and in the furtherance of end just referred to, there is also preferably provided an annular cap constituting restraining means for preventing, if abnormal operating conditions are experienced, an undue lifting or tilting of any section of the turnable member from its normal operating position on the supporting seat therefor.

3—The main beams or girders, while shallow in themselves, are located close to the top portion of the bowl shaped tank and are supported on the tank by short legs or intermediate members and the cage or drum above referred to is relatively short or shallow and extends downwardly substantially only that distance which is required for affording a proper connection to a rigid rake-arm structure, sometimes referred to as a rake carrying structure, which is provided for the carrying of raking blades that are dependably supported from the rake arm structure and that extend towards and in the immediate region of the bottom portion of the bowl shaped tank. The depending drum or cage essentially transmits the entire torque forces required for the turning of the rake arm structure whereby, incident to the turning or driving of the drum, there is effected the turning of the rakes or scrapers along closed paths over diverse sections of the floor or bottom of the bowl or tank. The rake carrying structure just referred to is preferably located above the normal or operative water level of the tank, which operative level is normally determined by the overflow weirs of the effluent launder section of the tank. The rake arm carrying structure is provided by two sets of arms connected so as to form a rigid cross construction, in which the arms of each set constitute or provide a rigid assembly comprising in effect a single beam which approaches, but which does not equal the full diameter of the interior of the bowl. The construction is such that an upper portion or member provides a direct connection or tension section between the uppermost portion of the arms and a lower section or member provides a compression section between the lowermost portion or section of the arms whereby the extensions or outer end portions of each set of arms are in effect provided by the end portion of a relatively continuous beam extending from one side of the tank to the other. The spider-like arm construction preferably comprises as a tension reinforcing element or member a smaller cross construction providing a reinforcing connection immediately above the central portion of the main cross arm construction referred to. This small upper cross is constructed so that at the upper portions thereof the members which are brought into intersecting relationship are suitably connected as by welding or by a gusset plate, so as to essentially provide a rigid top chord connection. The two cross members, namely, the small upper cross construction and the lower large main construction are directly connected, with the result that an exceedingly rigid rake carrying structure is obtained. This rake carrying structure is preferably provided by assembled I-beams, but it will be manifest that the assemblage of other structural shapes could be brought into effective

structural relationships and embody the teachings of the present invention.

4—The cage or drum above referred to had direct connection to the rake carrying structure preferably as the section immediately outside of the smaller cross construction mentioned. This connection is effected in any suitable manner either as by welding or through intermediate connections provided as by channel members con-

10 nected to the cage on the one hand and to the rigid rake carrying structure on the other hand at points of the latter intermediate or center portion thereof and the outermost end portions of the arm with the result that the cantilever effect 15 or "outhang" of the arms is correspondingly less than it would be if the arm carrying structure were supported solely at the center section thereof. The objects and aspects of the invention revolve about the features of construction above

20 referred to, whereby there is enabled to be realized a classifier of large capacity, a classifier rigid in construction, relatively self-contained, and simple, a classifier functionally effective for the operations to be carried out thereby and therein, 25 reliable in operation, requiring but a minimum of attention and maintenance, compact as to head-room requirements, and of shallow construction thereby adapting it for spaces whereby low head-room requirements can be met.

30 To attain these objects the invention, as already indicated, proposes to widen the effective base of support for the raking rotor, and at the same time to provide for a more effective torque transmission from a rotor drive head into the 35 rake arms.

To this end the invention provides and embodies in the drive head a torque transmitting element in the nature of a hollow member adapted to rotate about a vertical axis, such as the 40 drum or cage referred to, and which, as previously indicated, has bearing means adapted to support it from the top, and has fixed to its lower end portion a bladed raking assembly or spider construction. The method of fastening the raking 45 assembly or spider to the hollow member or cage is one characteristic of this invention, in that the effective free length or outhang of the rake arms also may be relatively reduced, while provision is made for the inner ends of the rake arms to brace each other within and through the cage or drum, thereby lending intrinsic stability to the rotor proper as well as to the rotor assembly as a whole.

According to one feature the inner ends of the 50 rake arms are joined in a central portion or intersection of the spider, which intersection is located substantially within and centrally of the 55 confines of the hollow torque transmitting element or drum.

In a preferred embodiment the raking spider 60 comprises a pair of intersecting horizontally extending elements at least one of which may be a through-going element of the character of a beam. Additional bracing or reinforcement of the intersection may be provided within the drum or cylinder in order to secure a desired degree 65 of rigidity and stability for the rake arms in operation. In this preferred embodiment the rake arms of the spider are located above the liquid level, so that an improved non-submerged drive 70 head arrangement for the spider may include a rising cylindrical portion connected at its lower end with the drive arms, a bull-gear fixed to and surrounding the top of the cylindrical portion, and annular bearing means to support the 75 bull gear for rotation of the spider.

Another advantage coincident with the attainment of improved stabilization in the operation of the rotor, lies in the fact that the guiding base for the rotor can be disposed horizontally, thereby reducing head room requirements relatively to a minimum.

The invention possesses other objects and features of advantage, some of which with the foregoing will be set forth in the following description. In the following description and in the claims, parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic 20 of my invention are set forth with particularity in the appended claims. The invention itself, however, both as to its organization and its method of operation, together with additional objects and advantages thereof, will best be understood 25 from the following description of a specific embodiment when read in connection with the accompanying drawings in which

Fig. 1 is a top view upon a bowl classifier,

Fig. 2 is a part sectional side view of the bowl 30 classifier shown in Fig. 1,

Fig. 3 is an enlarged longitudinal section through the bowl compartment of the bowl classifier, and improved rotary raking mechanism therein,

Fig. 4 is a perspective view upon the bowl compartment and improved rotary raking mechanism therein,

Fig. 5 is a detail perspective view of the raking 40 rotor with parts broken away to more clearly illustrate the invention.

The apparatus herein shown to embody the invention is a bowl classifier unit as illustrated in Figures 1 and 2, and which is known to include as essential portions thereof a primary separating compartment in the way of a relatively shallow and preferably circular sedimentation tank or bowl 10, and partly underlying the bowl a secondary separating compartment in the form of a substantially longitudinal classifier trough 11 having a suitably inclined bottom or deck 20 which is shown to extend from below the central portion of the bowl and at a suitable slope upwardly to a point beyond the margin of the bowl. The bowl is shown to have a shallow conical bottom portion 12 with an outlet opening 14 therein leading into the classifier trough 11 below. The bowl 10 also has a circumferential overflow weir 15 and associated therewith a circumferential overflow launder 16 having an overflow outlet at 17. The bowl 10 in this type of machine is provided with rotary raking mechanism herein collectively indicated by the numeral 18, which mechanism operates to transfer settled solids over the bowl bottom through the opening 14 into the classifier compartment 11 below. Since the design of this raking mechanism constitutes the essentials of this invention it will be described in all its details further below.

In the classifying compartment 11 there operates a reciprocating rake mechanism 19 for effecting the stepwise conveyance of heavier settled solids upwardly over the inclined bottom or deck 20 to emergence. This mechanism plays no direct part in this invention, and it is shown to be as of a

- standard type as found in Dorr classifiers and too well known to require specific description. Suffice it to say that a rake structure 21 is given a desired cyclic movement through an actuating mechanism which comprises a main crank shaft 22 and driving connections 23 and 24, consisting of links, and levers, and leading from the main crankshaft to the respective rake suspensions or rake hangers 25 and 26.
- 10 A cleanout opening 27 is indicated in the lower end of the classifying compartment to have a closure 28. Suitable structures 30 and 31 support the classifying and the bowl compartment respectively.
- 15 In the present embodiment the classifying compartment is shown to be equipped with a twin raking mechanism driven from a common main driving or crankshaft although at staggered phases. This indicates on the face of it a relatively larger capacity as compared with single rake classifiers and consequently also a relatively large bowl diameter—although the latter is not necessarily a function of the capacity of the classifier compartment—bearing on the fact that the larger bowl sizes are particularly benefited by the novel rotor drive head arrangement of this invention.

The apparatus so far described includes component parts basically known from the U. S. Patent 1,916,392. However, inasmuch as the invention now revolves primarily and more specifically around improvements in the design of the rotary raking mechanism previously designated by the collective numeral 18, for the sedimentation compartment or bowl 10, such rotary mechanism 35 will now be described in its details.

Referring particularly to Fig. 3, the rotary portion or rotor of the mechanism includes a spider formed by two pairs of arms 32 suitably connected to constitute a rigid cross structure having a point to constitute the intersection 33. Preferably one pair of arms 32 is formed by a through-going element 34, while the other two arms extend at right angles from the central portion of the through-going element to which they are shown to be fixed as by tie plates 35 and clips or other suitable means. The central portion of the rotary spider or cross, or the intersection, is reinforced and stiffened by an overlying smaller cross or element 37 including the central tie plate 38. To the lower side of the rake arms 32 are fastened raking blades 38a by means of brackets 38b, of I-shaped profile, such specific blade mounting being known.

Fixedly attached to the upper side of the rake arms 32 of the rotary spider and substantially encircling the intersection 33 thereof, is a cylinder, or drum, or hollow portion or hollow torsion member 39 constituting a cage dimensioned to rise just high enough to find suitable annular bearing support above the liquid level 18 in the bowl 10 and having longitudinal ribs 39b. The lower end of the cylinder 39 has a flange 39a by means of which it is attached to the arms 32 of the spider. The upper end of the cylinder 39 is crowned by a suitable annular member 40 having a toothed portion 40a so as to form a bull gear or worm-wheel adapted to receive driving impulse for the rotor. The rotary movement of the rotor is determined inasmuch as the gear or member 40 also constitutes an upper bearing race by which it is adapted to cooperate with an annular stationary bearing support or race which latter is represented by an annular stationary member 41. Anti-friction means or balls 42 are interposed between the bearing races or members 40 and 41.

A suitable connection between the worm-wheel 40 and the cylinder 39 is realized as by forming the worm-wheel 40 with a short upright cylindrical portion or rigid collar 43 adapted to fit around the upper end portion of the cylinder 39 and to be fixed thereto as by screw bolts 44.

The stationary bearing member 41 is formed substantially in the way of an annular trough in which the peripheral or toothed portion of the gear 40 may be housed. An annular cover portion 45 fits onto the trough and is attachable thereto by screw bolts 46. The annular trough 41 and the cover portion 45 therefor constitute in fact a casing which closes around the toothed portion 40a of the worm gear. Circular strips of felt or other suitable material are interposed at 47 and 48 respectively between the gear and the casing to form a dust proof closure between the relatively moving parts.

The stationary housing for the worm gear is supported upon a structure or system 49 which extends across the bowl 10 and has suitable end supports 50 fixedly associated with the marginal portion of the bowl.

The supporting structure 49 consists of a pair of parallel beams or channel irons 51 extending over and across the bowl, and suitably spaced from each other to straddle a center line of the bowl. Transverse or cross members or ties 52 are provided between the two beams and connected therewith as by clips or the like. There are also provided diagonal bracing 53, and transverse bracing 53a at the end of the beams 51. Thus is formed in the supporting structure 49 a centrally located square shaped frame portion in which lodges the cylinder 39 of the rotor, and upon which frame portion may be supported the stationary gear casing described above, through the intermediary of an apertured plate member 54 which fits over the square shaped central frame portion of the supporting structure, and upon which plate member the gear casing can be conveniently anchored by screw bolts 55 located in the corner portions of the plate member.

An annular feed arrangement encircles the cylinder 39 of the rotor. It comprises an annular feed chamber 56 having an inlet 57 and outlet openings 58 distributed along the bottom, a layer of concrete or other suitable material being applied to cover the bottom of the feed chamber to protect the same against abrasion from the solids carried by the feed. The annular feed chamber 56 is stationary and attached to and suspended from the lower side of the beams or channel irons 51. Furthermore, an annular horizontal baffle plate 59 is arranged below the annular feed chamber, and supported upon and rotatable with the rake arms 32. This baffle plate 59 closes against the cylinder 39 by having its inner edge portion intervene between the flange 39a of the cylinder 39 and the rake arms. Tie bolts 60 clamp the cylinder, the baffle plate 59 and the rake arms 32 together into a rigid unit or rotor. Fastening connections may also be provided between the cross member 37 and the cylinder 39.

Downwardly from the outer edge of the annular baffle plate 59 extends a skirt portion 61 which at its lower end is connected with a second annular baffle plate 62, this baffle plate being somewhat below the liquid level in the bowl. Still further, a cylindrical baffle 63 also supported upon the rake arms to rotate therewith, is arranged to surround the first-mentioned annular baffle plate 59. Finally, there is provided along the circumference of the second annular baffle plate 62 a

ridge or weir 63a which terminates just below but close to the liquid level 18 in the bowl.

The characteristics of a new drive head arrangement for the rotary raking mechanism are furthermore brought out in the perspective views shown in Figs. 4 and 5.

Fig. 4 illustrates the compactness of the drive head, and the improved manner of mounting and supporting the same relative to the bowl; whereas Fig. 5 shows more precisely and impressively the novelty which lies in the rotor structure itself, that is to say, it shows the novel manner in which a raking spider or cross is combined and connected with parts of the drive head; in other words, Fig. 5 illustrates the novelty which lies in the fact that by the structural combination of the spider with the cylinder 39 the stability of the rotor is increased inasmuch as the free length of the rake arms is relatively shortened as the central portion of the spider comes to lie within the boundary of the cylinder 39. Additional stiffening means may be provided for the spider within the cylinder 39, so as to make the rotor intrinsically as of great stiffness and stability, without necessitating the use of external bracing between the arms 32 themselves or between the arms 32 and the cylinder 39, such or similar bracing being unfeasible in view of interfering structure such as the stationary feed chamber 56 and/or the supporting beams 61.

Other factors in attaining a high degree of stability for the rotor lie in the relatively wide basis of support provided by the annular bearing; and further in the fact that the location of the rake arms above the liquid level reduces the necessary height of the cylinder 39 to a minimum as compared to its diameter, such minimum height being otherwise controlled by the vertical dimensions as required by the beams or channel irons 51 and by the feed chamber 56.

It is furthermore observed in this novel design that the diameter of the cylinder 39 may be freely chosen as large as reasonably desirable, in view of the fact that the feed arrangement is shown to be annular and is preferably so disposed that the feed will be introduced into the liquid in the bowl at a point which lies well beyond and spaced from the solids outlet zone of the bowl, so that in view of the shallowness of the bowl volume, short-circuiting of solids from the point of feed to the bowl outlet may be prevented. Consequently, it is a characteristic relationship of parts that the inside diameter of the annular feed arrangement is sufficiently large so that within its inner free space, the cylinder 39 can be accommodated, and the cylinder in turn may thus be chosen of an adequate diameter.

According to known practice, the outlet opening in the bowl bottom may be of plain circular shape located preferably in the center of the bowl; or the opening may be elongated and thereby conform more nearly to the width of the underlying classifier tank; or there may also be provided adjustable gate means for varying the size of the opening.

Driving means for the raking rotor may be of some suitable kind, and as indicated in Fig. 1 they may comprise a worm and worm shaft 64 mounted in the worm gear casing to drive the worm gear 40, a driven sprocket 65, a chain 66, and a driving unit which comprises a countershaft 68 coordinated to a motor 69 through a belt drive 70, motor 69 and countershaft 68 being carried by a plat-

form 71 upon the supporting structure or system 49.

In the normal operation of the bowl classifier which is broadly known, the raking rotor is kept rotating in the bowl 10 by its driving mechanism at a speed which is adequate to cause the raking blades 38a to advance settled solids at the rate desired, but without undue disturbance of the liquid in the bowl, while in the classifier compartment 11 the reciprocating rakes 21 of the twin rake arrangement are driven by their respective mechanisms to perform their bodily movements in a closed cyclic path.

Feed, such as for example a metallurgical pulp, enters the feed chamber 56 through the feed inlet 57 to be distributed to the various outlet openings 58 through which diverse streams of pulp leave the feed chamber to be intercepted by the underlying annular baffle plate 59. Here the feed is caused to spread radially into a shallow stream which precipitates over the outer edge of the baffle plate 59 while the cylindrical baffle 63 and the skirt portion 61 form the outer and inner limitations respectively between which the feed is confined in its downward movement and by which it is directed onto the second annular baffle plate 62 where it spreads further in a radial direction only to be introduced into the liquid body in the bowl itself radially and substantially at the liquid level as it traverses the ridge or weir 63a. Solids of the heavier type are now caused to settle out upon the bowl bottom as the liquid makes its way from the point of feed introduction to the peripheral overflow weir 15 of the bowl. Certain finer solids are carried off by the overflowing liquid while the settling portion of the solids is caught by the traveling raking blades and slowly advanced towards the outlet opening 14. With the improved construction of the rotary rake mechanism, the rakes or raking blades will have a firmer operating engagement upon the load of settled solids so that quivering of the rotor or rake arms will be eliminated or subdued. The sludge is thus gradually moved and allowed to drop through the opening 14 into the classifying compartment 11 where the rakes maintain a zone of agitation in which the solids undergo a kind of scrubbing treatment whereby a certain heavier fraction definitely settles out upon the inclined bottom or deck 12 of the classifier compartment, to be conveyed stepwise upwardly along the deck by the reciprocating movement of the rakes until it reaches a point of emergence and eventually a point of delivery from the classifier as the so-called rake-product.

At the same time certain fine sizes of solids which may have entered the classifier compartment will have been thrown back into suspension by the agitation and will eventually find their way back through the opening 14 into the bowl compartment and out through the bowl overflow.

The following material is incorporated as it may aid in a ready appreciation and understanding of certain expressions employed in the claims.

As to the bladed raking assembly or spider, the construction providing the lower intersecting arms 32 thereof may be referred to as a lower cross structure and the construction 37 providing the upper set of arms may be referred to as an upper cross structure which is in vertical alignment with and that overlies the large cross structure. The plate 35 which connects the lower portion of the long arms 32 may be viewed as a compression plate rigidly connecting

the lower arms so that a relatively continuous compression chord or section is provided for the resulting long beam construction which may be considered as extending from one side of the 5 tank to the other. The plate 38 of the smaller cross structure 37 unites the short arms thereof so that they are relatively rigidly connected, or in other words, so that the smaller cross structure constitutes a rigid, relatively self-contained 10 unit. This tie plate 38 may be viewed as a tension member connecting the upper portions of the arms constituting the small cross structure. The arms of the small cross structure are directly connected to the longer arms of the 15 lower cross structure and the smaller cross structure 37 may be viewed as constituting a tension section that connects the upper portion of the lower long arms 32, to wit, the aligned long arms 32 that extend radially in opposite directions 20 from the center. From one point of view this small upper cross structure constitutes the tying tension member for the arms of the large lower cross structure. From another point of view the connected upper and lower cross structures result 25 in a strong composite cross structure in which the structural members providing the arms, or out-hanging portions thereof, are connected in a manner whereby the rake carrying arms are parts of a stiff or rigid beam structure extending approximately from one side of the tank to the 30 other side of the tank.

The parallel beams or channels 51 may be viewed and arbitrarily termed as horizontally and longitudinally extending main beams or girders 35 that are transversely spaced at equal distances from and at opposite sides of the vertically extending axis about which the raking assemblage turns, or as otherwise expressed, about the vertically extending axis or center of the tank or 40 bowl. The transverse tie members 52 may be viewed as horizontally but transversely extending members which are longitudinally spaced. These cross members 52 are connected to and serve to connect the main longitudinal members 45 or beams 51. The cross members 52 are also located at equal distances from the opposite sides of the axis just referred to and with the main beams define a box-like section providing a vertically extending opening which is preferably substantially square in horizontal cross section. 50 This opening provides a receiving space into and downwardly through which the rotatable cage or hollow drum member 39 extends. The box-like section provided by the connected main longitudinal beams and transverse beams constitutes 55 or provides a main frame or structural base on which the annular stationary turntable member 41 is fixedly secured. In other words, this box-like section of the frame construction provides 60 a structural foundation, which through the medium of the annular stationary member 41 of that which may be viewed and termed as a turntable construction, is fixedly secured and positioned in respect to the bowl or tank 10. The annular 65 cap, crown or cover member 40 which comprises and provides the worm wheel teeth 40a may be viewed as the rotatable or turnably supported member of the turntable construction and it is to be noted that the annular cover portion 45 is 70 detachably secured to the annular stationary member 41. By and because of the cover 45 in the relationship shown, there is provided means functioning to prevent any substantial tilting of the turntable member of the turntable construction from the seating position provided there-

for. In other words, according to the construction just referred to, there results the large horizontal type of bearing which can be relied upon for properly supporting the turnable raking and scraping assembly and for maintaining said assembly against tilting from the desired normal operative position therefor.

What is claimed is:

1. A two compartment classifier having a lower classifying tank provided with an inclined deck and a solids agitating and conveying mechanism therein for advancing settled solids up along said deck, an upper bowl-shaped sedimentation compartment having associated therewith a rotatable raking structure provided with rotatable rake arms carrying raking blades and adapted for operation with respect to a load of settled solids in the bowl, means for operatively supporting the rotatable raking structure, means for feeding to the classifier a liquid solids mixture to be treated therein, an effluent overflow discharge, and a discharge for the solids from said tank; characterized in that the rotatable raking structure comprises a self-contained rake arm structure constituting a rigid spider having substantially radial arms rigidly and directly interconnected at the center of the spider, and by and from which arms the raking blades are supported; and in that the rotatable structure further comprises a movable annular turntable member, a hollow torsion member of a suitable width and coaxial with and rigidly interconnecting said turntable member and the self-contained rake arm structure, which hollow torsion member thus overlies the center portion of the spider and thereby defines inner and outer rake arm portions of the spider, the width of said torsion member being such as to establish a ratio of lengths of outer to inner rake arm portions by virtue of which ratio the rotatable raking structure is adapted to assure a desired rigidity and operating stability with regard to stress reaction from the operating load; and furthermore in that the means for supporting the rotary raking structure comprise structure complementary to said annular turntable member for sustaining the same in predetermined operative relation to the bowl.

2. An apparatus as defined in and by claim 1, which is further characterized by the fact that the rake arm construction comprises a centrally located relatively short-armed auxiliary spider structure which corresponds to and overlies substantially in vertical alignment the inner or central arm portions of the rake arms.

3. An apparatus as defined in and by claim 1, which is further characterized by the fact that the rake arm construction comprises a centrally located relatively short-armed auxiliary spider structure as a means to effect reinforcement and increased total rigidity of the rake arm construction, which reinforcing spider corresponds to and overlies substantially in vertical alignment the inner central arm portions of the rake arms, and that the reinforcing spider structure substantially lodges within the boundaries of the hollow of the torsion member.

4. For use in a classifying apparatus a self-contained rake structure comprising a rake arm cross structure adapted for rotary raking operation in which the connected rake arms extend substantially in an identical plane, and are essentially provided by structural shapes; a relatively short-armed although similar auxiliary cross structure overlying in vertical alignment

the central portions of the rake arm cross for reinforcement and increased rigidity thereof, and having its connected short-arms also essentially provided by structural shapes; scraper 5 blades providing raking elements arranged in series along and from each of said rake arms, a hollow torsion member coaxial with the rotary axis of the cross structure and rigidly connected thereto at points upon the rake arms, which lie intermediate the inner and the outer ends thereof; and an annular turntable member coaxial with the torsion member and rigidly connected with the free end thereof.

5. For use in a classifying apparatus having positive rotation imparting driving means, a rotatably mountable rigid rake construction comprising a rigid rake arm cross structure, scraper blades providing raking elements arranged in series along and from each of the rake arms, a 10 hollow torsion member coaxial with the rotary axis of the cross structure and rigidly connected thereto at points upon the rake arms, which points lie intermediate the inner and the outer ends thereof; and an annular turntable member 15 coaxial with the torsion member and rigidly connected with the free end thereof and adapted to receive positively acting rotary driving impulse from said driving means when operatively mounted for rotation in said classifying apparatus.

6. A classifier according to claim 1, in which the torsion member is a cylinder substantially and approximately as wide as it is high.

7. In a classifier apparatus a relatively shallow bowl-shaped sedimentation tank with a bottom discharge for settled solids; means for feeding liquid solids mixture to the tank; effluent overflow means functioning in the withdrawal of supernatant liquid from the tank; a rotatable raking assembly which by way of the rotation of a raking construction rotatable about a vertical axis functions to convey settled solids over the tank bottom to said discharge, and which assembly comprises a radial rake arm construction having the inner ends of its rake arms rigidly and directly interconnected, a hollow torsion member of a suitable width coaxial with the rotary axis of the rake arm construction and rigidly connected thereto at points upon the rake arms, which lie intermediate the inner and outer ends thereof, and which torsion member is dimensioned as to its relation of height to width to give the rotatable raking construction per se a desired operating stability and rigidity, a rotatably mountable annular turntable member coaxial with the torsion member and rigidly connected with the free end thereof and rotatable therewith and with the rake arms; an annular stationary turntable member adapted for operatively supporting the rotatable turntable member and thereby said raking construction; a shallow frame superstructure traversing the tank and having fixed and rigid relationship thereto, and composed mainly of a pair of main beams straddling the center of rake rotation, and of cross-connections therefor, which frame is adapted and designed in adaptation to and substantially closely surrounding said torsion member and for supporting said stationary turntable member to establish operative raking relation between the rotatable raking construction and the tank bottom.

8. Apparatus according to claim 7, in which the raking arms proper extend above although near to the liquid level in the tank, and in which

the torsion member is a cylinder extending from the rake arms upwardly and above the liquid level, the height of which torsion member is approximately equal to or less than its width.

9. A settled solids raking device according to claim 7 in which the raking arms proper extend above although near to the liquid level in the tank, and in which the torsion member is a cylinder extending from the rake arms upwardly and above the liquid level, the height of which torsion member is approximately equal to its width.

10. A settled solids raking device according to claim 7, in which the raking arms proper extend above although near to the liquid level in the tank, in which the feeding means comprise an annular feedwell surrounding the torsion member and interposed between said raking arms on the one hand, and said main beams on the other hand, and supported from said main beams, and in which the height of the torsion member corresponds to the aggregate height required by the beams and the annular feedwell, and in which the height of the torsion member is approximately equal to its width.

11. In a classifier apparatus having positive rotation imparting driving means, a relatively shallow or bowl-shaped sedimentation tank having a bottom discharge for settled solids, effluent overflow means, means for feeding liquid solids mixture to the tank; a rotatable assembly which by rotation of a raking construction rotatable about a vertical axis functions to convey settled solids over the tank bottom to said discharge,

and which assembly comprises a radial rake arm construction having the inner ends of its rake arms rigidly and directly interconnected, a hollow torsion member of suitable width coaxial with the rotary axis of the rake arm construction and rigidly connected thereto at points upon the rake arms, which lie intermediate the inner and the outer ends thereof, which torsion member thus defines inner and outer rake arm portions of the radial rake arms, and which torsion member furthermore is dimensioned as to height and width to establish a relation of said outer and inner rake arm portions, by virtue of which there is given said rotary raking construction a desired operating stability and rigidity; a rotatable annular turntable member coaxial with the torsion member and rigidly connected with the free end thereof and rotatable therewith and with the rake arms, and adapted to receive driving impulse from said rotation imparting driving means; an annular stationary turntable member adapted for operatively supporting said rotatable turntable member and thereby said rotatable raking construction; a frame structure fixedly supported upon the tank and surrounding said torsion member and adapted for supporting said stationary turntable member to establish operative raking relation between the rotatable raking construction and the tank bottom, and also adapted to support said driving means; and an annular cover means detachably secured to the stationary turntable member so as to overlie the marginal portion of the rotatable annular turntable member and arranged for serving as a member for restraining tilting movement of the rotatable turntable member away from the operative seating position therefor whereby the rotatable raking construction will be restrained against any substantial tilting movement during the normal operation thereof.
